RICHARD WEBB BURNETT AND HENRY H. VAUGHAN, OF MONTREAL, QUEBEC, CANADA.

RAILWAY FREIGHT-CAR.

1,130,791.

Specification of Letters Patent.

Patented Mar. 9, 1915.

Application filed June 12, 1914. Serial No. 844,633.

To all whom it may concern:

Be it known that we, RICHARD WEBB BURNETT and HENRY H. VAUGHAN, citizens of the United States, residing at Montreal, 5 Canada, have invented a certain new and useful Improvement in Railway Freight-Cars, of which the following is a full, clear, concise, and exact description, reference being had to the accompanying drawings, 10 forming a part of this specification.

Our invention relates to improvements in railway freight cars, particularly the end construction of said cars.

In the practical operation of railroads, 15 freight box cars are constantly required to carry many different characters of freight, and in the loading and unloading thereof the end sheathing of the car frequently becomes battered and injured, and by reason 20 of this injury, as well as by reason of the injury from shocks received through shifting of freight within the car in transit, the ends of the car frequently become weakened, requiring repair and reinforcement. Here- 25 tofore, it has been the common practice in making such repairs on box car ends to remove the inner sheathing and replace the same with new material. In the removal of the sheathing, requiring the pulling of the 30 nails and the removal during the repair of the bracing which the sheathing itself affords, it occurs that the end of the car is sometimes further weakened and distorted. The ends of cars sometimes sag and become 35 distorted through ordinary use or overloading, or the shifting of loads, because of an almost complete reliance in car construction upon the car sills or underframe as the load supporting member.

40 The object of our invention is to remove these difficulties in car repair work and to provide a means of reinforcing car ends adapted to afford a rigid end construction.

A further object is to provide in new construction of cars a firm, durable and rigid car end, and to employ parts of the car body above the underframe to assist in supporting the ends of the underframe.

The means employed to accomplish these 50 objects are fully described hereinafter, and illustrated in the accompanying drawings, in which—

Figure 1 is an end view of a railroad box car embodying our invention; Fig. 2 is an 55 enlarged longitudinal vertical section of the end of the car taken on line 2—2 of Fig. 1,

the middle portion being broken away; Fig. 3 is a cross section taken on line 3—3 of Fig. 2; Fig. 4 is a detail showing the forward end of the car's center sills and some of the adjacent parts connected therewith; Fig. 5 is a detail showing in plan view partly in horizontal section the forward ends of the center sills and parts secured thereto; Fig. 6 is a cross section enlarged, taken on line 6—6 of Fig. 4; Fig. 7 is an enlarged section taken on line 7—7 of Fig. 4.

Referring to the drawings, the numeral 8 indicates the end of a box car body, having a roof 9, the end frieze 10, the end facia 11, 70 the end plate 12, the outer end facing 13, which at its upper portion extends between the end facia and the end plate, the bolts 14—14 being provided to secure the end facia and end plate together.

The numeral 15 indicates the usual end lining of the car, 16 the car floor, 17 the end sill, 18 the buffer block, 19 the buffer face plate, 20 the draw bar carry-iron, 21—21 the center sills, which are preferably Z-bars 80 passing over the body bolster, not shown in the drawings. The said Z-bars are preferably rolled steel and extend from the end sill at one end to the end sill at the other end of the car underframe, being adapted to be suitably secured to the body bolsters. Dependent from the ends of each center sill and secured to the inner face thereof by the rivets 23—23 is a draft sill 24, a pair oppositely faced being provided at either end of 90 the car underframe.

In preferable construction, each draft sill is of greater vertical width than the center sill to which it is attached, and is provided at its forward end with an inwardly turned 95 flange 25, adapted to engage the end sill reinforcing plate 26. Suitable stop members 27 are secured to the inner face of each draft sill; the stop members being oppositely arranged near the ends of the car underframe. The draft members pass over the adjacent body bolster and are provided at their outer faces with the reinforcing angle irons 270, the said angle irons being each secured by suitable rivets to the lower flange 100 28 of the center sills and to the draft sills and abutting at their rear ends 29 against the forward face of the body bolster. Each draft sill is also provided along the outer portion of its outer face with a longitudinally extending angle iron 30, which is upwardly turned at its rear end along the 110

oblique portion 31 of the draft sills. Each pair of draft sills is tied together by a transverse plate 32, suitably riveted to flanges 33 with which the oblique portion 5 of each draft sill is provided. The draft sills at their forward ends extend underneath the end sills 17 and the buffer block 18, and are rigidly held to the buffer block by bolts 34 which connect the buffer block 10 to the draw bar angle iron 25. The numerals 35—35 indicate the usual end posts of the car, to each of which there is secured a Z-bar 36, each Z-bar extending from the plane of the lower face of the end sills 17 15 to the roof of the car. On the inside of the car the end is provided with additional end lining 37, made preferably of heavy material and placed crosswise the end of the car from the floor thereof to the end plate, as 20 illustrated in Fig. 2 of the drawings. Bolts 38—38 passing through the additional end lining 37, the end lining 15, the outer facing 13, and the flanges 39 of the Z-bars 36, rigidly secure the members forming the end 25 of the car together. The end sill reinforcing plate 26 is securely bolted to the end sills, and is also secured to the draft sills by suitable means, preferably the rivets 41—41 passing through the vertical flanges 30 42 of the end sill reinforcing plate 26 and through the flanges with which the draft sills are provided. Bolts 43—43 passing horizontally through the flanges 39 of the Z-bars 36, through the outer face 13, the 35 end sills 17, and the end sill reinforcing plate and vertical flange 42, serve to rigidly secure these parts together. By reason of the rigid union between draft sills and center sills, the draft sills are virtually parts 40 of the center sills. Through the end sill reinforcing plate and end sill, the end of the car is employed to assist in supporting the ends of the center sills 21 and the other longitudinal sills of the car, including the intermediate sills 45. It is desirable that the 45 end sill reinforcing plate 26 be arranged with a horizontal flange 44 resting upon the upper face of the end sill 17 and passing underneath a portion of the car's end, preferably the ends of the flooring and the inside lining 15 and additional lining 37, as illustrated in Fig. 2 of the drawings.

It will be observed that among the novel 55 elements in car construction herein described are the feature of the Z-bar members vertically arranged at the ends of the car and secured to the car body above the underframe and to the end sill, and adapted not only to reinforce car end posts where the same are employed, and to repair car 60 end posts, but may be employed in repair work in connection with a cracked end sill, reinforcing the same and saving the necessity of the removal thereof. Particularly

are these members effective in assisting to employ the car body above the underframe to aid in supporting the ends of the longitudinal sills of the car.

A further novel element is that of the additional bracing lining 37, which not only affords a strong car end to prevent bulging of the same when loaded with grain or similar freight, for instance, and when subjected to the heavy shocks of service, but also affording a rigid car end, which with the Z-bar members aids in supporting the ends of the underframe through the other parts of the car body.

A further novel element is the employment of an end sill reinforcing plate extending over the end sill, which plate, together with the end sill, affords a rigid connection of the longitudinal sills and end sills of the car, and makes a rigid connection between the ends of the car and the longitudinal sills.

The structure herein described consists of parts easy of application in repairing and reinforcing the ends of cars, and one desirable in new car construction, the novel elements of which just mentioned, together with other novel elements hereinbefore described, are more particularly set forth in the following claims.

We claim:

1. In a railroad car, the combination with the end of a car having end posts therein, of a reinforcing member secured to each end post, an additional inner lining and means 100 for securing the additional lining and reinforcing members together.

2. In a railroad car, the combination with the end of the car having end posts, of Z-bar members extending longitudinally of 105 the posts, an additional inner end lining, and means passing through the end of the car for connecting the Z-bar members to the additional inner lining.

3. In a railroad car, the combination with 110 a car end, end sill and center sills, of reinforcing members above the outer face of the end of the car, an additional end lining on the inner face of the end of the car, and an end sill reinforcing plate secured to the longitudinal sills and passing above the end sill and underneath a portion of the end of the car.

4. In a railroad car, the combination with 115 a car end, end sill and center sills, of reinforcing members above the outer face of the end of the car, an additional end lining on the inner face of the end of the car and an end sill reinforcing plate secured to the center sills and passing above the end sill and underneath a portion of the end of the car to support same, the reinforcing members being secured to the end sill and through the end of the car to the additional inner lining.

5. In a railway car, a car end having end 120

posts therein, inner and outer lining associated with such end posts, an additional inner end lining and reinforcing members extending along the outer faces of the end 5 posts and means connecting the reinforcing members with the additional inner end lining.

6. In a box car having an end wall formed of wooden posts and an outer lining secured 10 thereto, means for reinforcing said end wall comprising iron beams alined with and secured to said wooden posts and on the outer side of said outer lining.

7. In a box car having an end wall formed 15 of wooden posts and an outer lining secured thereto, the combination with means for reinforcing said end wall comprising commercially rolled iron beams alined with each of said posts and secured thereto and on the

outer side of said lining, of a strengthening 20 plate secured to the center sills of the car and to the end sill thereof.

8. A box car having center sills and an end wall and means for reinforcing said end wall, the end wall being formed of wooden 25 posts and an outer and inner lining secured thereto, said posts being arranged outside of the line of the center sills, and said reinforcing means comprising commercially rolled beams bolted to said posts on the 30 outer sides thereof.

Montreal, May 19, 1914.
